UNITED STATES PATENT OFFICE.

OTTO, LEON KIESELBACH, OF NEW YORK, N. Y.

METHOD OF MAKING TEA BALLS.

Original application filed October 8, 1923, Serial No. 667,239. Divided and this application filed January 17, 1924, Serial No. 686,805.

To all whom it may concern:

Be it known that I, OTTO LEON KIESELBACH, a citizen of the German Republic, and resident of New York, Borough of Bronx, 5 and State of New York, have invented certain new and useful Improvements in Methods of Making Tea Balls, of which the following is a specification.

The present invention has relation to tea balls or containers for holding the leaves of tea or other materials from which an infusion or extract may be made by immersion in liquids of suitable temperature, the same being a division of my copending application, filed Oct. 8, 1923, Serial No. 667, 15 239. More particularly the present invention relates to a class of perforated metal containers adapted to fully inclose a sufficient quantity of the material for a single 20 individual requirement.

One of the objects of the invention is to provide a container of simple construction that may be made from a single blank or sheet of material without waste thereof.

25 A further object is to provide a container having a shape adapted to offer the greatest strength and resistance for the amount of material used in its formation, thus permitting the use of relatively thin material in 30 its construction.

A further object is to provide a container having similar triangular faces which when turned or agitated will permit the contents to freely flow by gravity to the lowermost 35 face.

A further object is to provide means for movably suspending or agitating the container, or allowing the same to rest upon any one of its several faces to effect a more rapid 40 infusing action.

As further object is to provide a method of construction whereby the container may be formed into the desired shape from a single piece of material, provided with an open 45 mouth through which the material may be inserted, and closed therein by joining together the free edges of the mouth.

For further comprehension of the invention, and of the objects and advantages 50 thereof, reference is had to the following description and accompanying drawings, and to the appended claims in which the various features of the invention are more particularly pointed out.

55 Figure 1 of the drawings is a view show-

ing an extended blank from which the improved tea ball is adapted to be made.

Figure 2 is an end view showing a step in the construction, in which the blank is shaped tubular, with its opposite ends joined together by a seam.

Figs. 3, 4 and 5 show respectively side, end and edge views of the next following step in which the opposite plates at the lower end of the tube are contracted in wedge 65 form, with a tag-string introduced therebetween.

Figs. 6 and 7 show views corresponding respectively with Figs. 3 and 4, and which further show the edges of the contracted 70 plates joined together with a double seam, and the tag-string doubled up with the seam and secured thereby, the opposite end of the tube being left open at this step for introducing the material to be inclosed. 75

Figs. 8 and 9 show views corresponding respectively with Figs. 6 and 7 and which also show the opposite plates at the opposite or upper end of the tube to be similarly contracted in wedge form, and, as indicated 80 by the broken lines 8^a, the contraction from the latter position causes the plates to be extended in a right-angle direction as indicated in Fig. 9.

Figs. 10 and 11 show views corresponding 85 respectively with Figs. 8 and 9 and which also show the upper edges of the plates as being seamed over to securely seal the contents of the container.

As shown in the drawings numeral 10 designates a blank consisting of a rectangular piece of relatively thin material, preferably aluminum foil, provided with suitably disposed perforations 11, and score lines 12, the latter being arranged in triangular relation, 90 corresponding with the bends or folds to be made in the blank.

In the formation of the article the blank is first folded over in tubular form with the ends 13 joined together and forming, as 100 shown in Fig. 2, a seam 14, the score lines 12 dividing the surface of the tube into four equal triangular spaces. The side walls of the tube at its lower end are then closed together, a tag-string or corresponding flexible connection 15 having been introduced therebetween, as shown in Figs. 3, 4 and 5, the lower end of the walls being then folded over to form a double seam 16, adapted to 105 form a closed joint and securely hold the 110

string, as indicated in Figs. 6 and 7. At this point in the forming operation the upper end 17 of the tube will be left open to receive the material to be introduced there-
 5 in and after the same has been inserted the upper edges of the tube will be closed together as shown in Figs. 8 and 9 and closed with a seam 18 adapted to securely retain the contents within the container, the closed
 10 seam being indicated in Figs. 10 and 11 which show side views of the finished container taken at right angles to each other.

It will also be seen that the closing operations of the lower and upper edges of the
 15 tube are made respectively at right angles to each other, and that the effect thereof is to bend the tube along the corresponding score lines 12 and form a closed container having four triangular perforated faces
 20 adapted by means of the flexible cord or connection to be immersed in a liquid for obtaining the desired infusion.

What I claim as my invention and desire to secure by Letters Patent, is:

25 1. The method of forming a container having four triangular faces, consisting in folding over a sheet of material and joining together a pair of its opposite edges to form a tube, and then closing and joining
 30 together the edges at opposite ends of the tube in planes extending in angular relation to each other.

2. The method of forming a container having four triangular faces, consisting in folding over a sheet of foraminous material and joining together a pair of its opposite edges to form a tube, and then closing and joining together the edges at opposite ends of the tube in planes extending in angular
 40 relation to each other.

3. The method of forming a container having four triangular faces, consisting in folding over a sheet of material and joining together a pair of its opposite edges to
 45 form a tube, then closing and joining the edges of one end of the tube together and leaving the opposite end thereof open for the reception of the material to be introduced therein, and then closing and joining
 50 the edges of said opposite end in a plane extending at substantially right angles to that of the first-mentioned end and forming a closed container having four triangular faces.

55 4. The method of forming a container from a single sheet or blank, consisting in forming a series of triangularly arranged score lines in said blank, then folding over the blank and joining together a pair of
 60 its opposite edges to form a tube, then closing and joining the edges of one end of the tube together and leaving the opposite end thereof open for the reception of the mate-

rial to be introduced therein, and then closing and joining the edges of the said opposite end of the tube in a plane extending at substantially right angles to that of the first-mentioned end and forming a closed container having four similar triangular faces.

65 5. The method of forming a container having four triangular faces, consisting in folding over a sheet of perforated metal and joining together a pair of its opposite edges to form a tube, and then closing and joining together the edges at opposite ends of the tube in planes extending in angular relation to each other.

70 6. The method of forming a container from a single sheet or blank of perforated metal, consisting in forming a series of triangularly arranged score lines in said blank, then folding over the blank and joining together a pair of its opposite edges to form a tube, then closing the opposite ends of the tube along said score lines and joining the edges thereof in planes extending in angular relation to each other and forming a closed container having four triangular faces.

75 7. The method of forming a container from a single sheet or blank of perforated metal, consisting in forming a series of triangularly arranged score lines in said blank, then folding over the blank and joining together a pair of its opposite edges to form a tube, then closing one end of the tube along said score lines and joining the edges thereof together and leaving the opposite end of the tube open for the reception of the material to be introduced therein, and then closing the opposite end of the tube along said score lines and joining the edges thereof together in a plane extending at substantially right angles to that of the first-mentioned end and forming a closed container having four triangular faces.

80 8. The method of forming a container, consisting in folding over a blank and joining together a pair of its opposite edges to form a tube, then closing one end of the tube and inserting between the walls thereof an end of a tag-string, then joining by double seaming the edges of the end of the tube thus closed together with the tag-string and leaving the opposite end of the tube open for the reception of the material to be introduced therein, and then closing and joining together the edges of the said opposite end of the tube in a plane extending at substantially right angles to that of the first-mentioned tube end and forming a closed container having four triangular faces.

85 9. Signed at New York, county of New York and State of New York, this 15th day of January A. D. 1924.

OTTO LEON KIESELBACH.
